UNITED STATES PATENT OFFICE.

WALTER P. MAY, OF ST. LOUIS, MISSOURI, ASSIGNOR OF ONE-HALF TO SHELLIE ANDREWS, OF ST. LOUIS, MISSOURI.

CHAUFFEUR'S SANDAL.

1,335,346.

Specification of Letters Patent. Patented Mar. 30, 1920.

Application filed June 23, 1919. Serial No. 306,006.

To all whom it may concern:

Be it known that I, WALTER P. MAY, a citizen of the United States, residing at St. Louis, in the county of St. Louis and State 5 of Missouri, have invented certain new and useful Improvements in Chauffeurs' Sandals, of which the following is a specification.

This invention relates to boots and shoes, 10 and more especially to protectors therefor; and the object of the same is to produce a device in the nature of a sandal for ready application to a boot or shoe in order to protect the same against the wear which occurs 15 at certain points incident to certain occupations. More especially the sandal is designed to protect the sole where it wears by constant contact with the pedal or pedals, and also incidentally to protect the counter 20 which frequently strikes other projections above the automobile floor.

The object of the invention is obviously to protect the foot wear of the chauffeur, and the ordinary or expensive shoes or slippers 25 of male and female automobile drivers.

In addition to its general features of construction, the invention includes specific details which render the sole of the protecting sandal quite flexible beneath the instep. 30 The preferred construction of the device is set forth below and shown in the drawings wherein:

Figure 1 is a plan view and Fig. 2 is a side elevation partly in section.

The protector comprises a sole made up of three members which may well be called the main sole 1, the insole 2, and the intermediate sole 3, and collectively these members have the thickness of two ordinary shoe soles. The main and inner soles are stitched together around their edges as shown at 4, and these stitches may pass through the edges of the intermediate sole or not, and if not, it is 45 obvious that the intermediate sole will be to an extent free for slight movement between the other soles when they flex. The main and inner soles extend from the toe 5 back to a point 6 where they are cut off 50 straight at their rear ends and stand flush with each other, while the intermediate sole 3 extends from said toe back to a point 7 somewhat forward of the rear end 6 of the other soles. This leaves the protector be-

tween the points 6 and 7 having a sole of 55 only two layers so that naturally it is a little more flexible beneath the arch than elsewhere. In order to increase this flexibility the insole 2 is cut out at 8 from its rear end 6 forward to a point 9 somewhat in advance 60 of the rear end 7 of the intermediate sole, and within the cut out between the lines 6 and 7 the protector therefore has but a single layer. The result is that the forward portion of the sole where most wear occurs 65 is quite heavy and to an extent unyielding, but the rearward portion may flex when the wearer walks.

This sandal has no upper. At its rear it has a wide counter 10 of pliable leather 70 whose front ends are turned downward and inward and stitched between the insole 3 and the main sole 1 as shown at 11. At its front end a strip 12 leads upward and rearward from the toe 5 and is slotted to form loops 13 75 and 14. From its sides rise straps 15, one of which passes through the front loop 13 and is connected with the other by a buckle 16. From the counter rise oblique straps 17, one of which passes through the rear loop 14 80 and is connected with the other by a buckle 18.

The device may be made in rights and lefts, although this is not absolutely necessary. It may be made and sold and used in 85 pairs, or a protecting sandal may be applied only to the foot where the most wear occurs. By preference the sandal is constructed entirely of leather, but the widest latitude in 90 this respect is reserved, especially with respect to the sole. The members of the sole may be of different material from each other, and the intermediate sole particularly might be of material of widely different nature, possibly of metal, although if metal is 95 employed, I would prefer a metal which will not rust. Other fastening means than buckles may be employed, and also other fastening means than stitches. In the use 100 of the sandal it is obviously slipped onto the foot over the boot or shoe or slipper which is to be protected, and its buckles or other adjustable fasteners may be set up later or may be set up in advance so that the sandal 105 may be slipped on and off at will. Whatever the wearer's occupation, the sole is now thoroughly protected and is permitted to flex when the wearer walks about, and the

wide strap or counter around the counter of the wearer's shoe or slipper will thoroughly protect the finest foot wear, even though it be of cloth, suede, or the like. Owing to the size or adjustability of this device, it is possible to apply it to the foot over a rubber if it should be so desired.

Having thus described the invention, what is claimed as new is:

- 10 1. A chauffeur's sandal comprising a sole having its rear end terminating at a point beneath the arch, a counter connected at its front ends with the rear end of the sole, a strap extending from the toe to the rear over the sole and having two loops, straps rising from the sides of the sole and one of them passing through the front loop, means for adjustably connecting these straps with each other, straps rising obliquely from the front ends of the counter and one of them passing through the rear loop, and means for adjustably connecting these straps to each other.
2. In a protector for shoes, a sole made up of outer and inner layers of a length to extend from the toe to a point beneath the arch and there terminating substantially flush with each other on a transverse line, means connecting said layers around their edges, and an intermediate layer of a length to extend from the toe to a point forward of said transverse line; combined with adjustable means for fastening the protector

to the bottom of the sole of an ordinary shoe. 35

3. In a protector for shoes, a sole made up of outer and inner layers of a length to extend from the toe to a point beneath the arch and there terminating substantially flush with each other on a transverse line, 40 the inner layer having a cut out between its side edges and extending from its rear end forward, an intermediate layer extending from the toe to a point in rear of the front end of said cut out but forward of 45 said transverse line, and means for attaching the layers to each other; combined with adjustable means for fastening the protector to the bottom of the sole of an ordinary shoe. 50

4. In a protector for shoes, a sole made up of outer and inner layers having their rear ends terminating at a point beneath the arch, means connecting said layers around their edges, and an intermediate layer of a 55 length to extend from the toe to a point forward of the rear ends of the outer and inner layers; combined with adjustable means for fastening the protector to the bottom of the sole of an ordinary shoe. 60

In testimony whereof I affix my signature.
